UNITED STATES PATENT OFFICE.

JOHN McDONALD, OF BRADFORD, PENNSYLVANIA, ASSIGNOR OF ONE-HALF TO H. HARRINGTON, OF BRADFORD, PENNSYLVANIA.

PIPE-CO尤PLING.

SPECIFICATION forming part of Letters Patent No. 784,416, dated March 7, 1905.

Application filed September 24, 1904. Serial No. 225,807.

To all whom it may concern:

Be it known that I, JOHN McDONALD, a citizen of the United States, residing at Bradford, in the county of McKean and State of Pennsylvania, have invented new and useful Improvements in Pipe-Couplings, of which the following is a specification.

This invention relates to pipe joints or couplings.

10 In practice it is found that after pipe-couplings such as are used upon gas-mains and the like have been installed for several years they become worn, loose, or rusted in such manner as to permit leakage. In order to prevent 15 this leakage, it is necessary generally to renew the coupling. This operation is doubly expensive on account of the cost of the couplings themselves and of the labor and time which is necessary to effect their renewal.

20 The principal object of this invention is to avoid the necessity of replacing the coupling after it has been in use for an extended period of time.

25 Further objects of the invention are to improve, simplify, and strengthen the construction of pipe-couplings; furthermore, to decrease the expense attending their manufacture.

With the foregoing and other minor objects 30 in view, which will appear as the description proceeds, the invention consists in a pipe-coupling provided with structural features which adapt it to be effectually soldered after it has been in use for a period of time and shows signs of leakage.

35 The invention also resides in the particular combination and arrangement of parts and in the precise details of construction hereinafter described and claimed as a practical embodiment thereof.

In the accompanying drawings, forming part of this specification, Figure 1 is a longitudinal central section, partly in elevation, of a pipe-coupling constructed in accordance with 45 the invention. Fig. 2 is an end view of one of the collars. Fig. 3 is a similar view of one of the rings. Fig. 4 is a similar view of one end of the sleeve.

Like reference-numerals indicate corresponding parts in the different views. 50

The reference-numerals 1 and 2 indicate pipe-sections which are adapted to be joined together by means of the improved coupling which constitutes the subject-matter of this invention. The pipe-sections 1 and 2 are fitted into the opposite ends of a sleeve 3, which is formed with flaring ends 4 and with an interiorly-disposed annular shoulder 5, against which the pipe-sections abut. The sleeve 3 is also formed with a portion 6, having a plurality of flattened faces to receive a wrench. Each of the flared ends 4 of the sleeve 3 is formed with a threaded portion 7, an annular groove 8, and a plurality of longitudinal grooves 12, which extend through the screw- 65 threads 7 and annular groove 8.

Surrounding each of the pipe-sections 1 and 2 and located in one of the flaring ends 4 is a packing-ring 9, which is constructed, preferably, of rubber or other compressible material suitable for the purpose. The packing-ring 9 is held in position by means of a metallic ring 10, having on the periphery thereof a plurality of ears or lugs 11, which are adapted to fit into the longitudinal grooves 12 75 in the flared ends of the sleeve 3. The ears or lugs 11 serve to prevent the metallic ring 10 from rotating, and thus tearing or abrading the packing-ring 9. In addition to the ears or lugs 11 the metallic ring 10 is formed 80 with an annular rib 13, which is designed to bite into the packing-ring 9 and cause the expansion thereof against the pipe-coupling, thus preventing any leakage of the joint. The metallic ring 10 is forced against the packing-ring 9 by means of a collar 14, which is formed with suitable screw-threads to engage the threads of the sleeve 3. As shown in Fig. 1, the collar 14 is concentrically removed from the pipe-section, as indicated at 15, and is 85 formed at its outer end with an annular cut-away portion 16, which constitutes a flaring entrance to the annular chamber between the collar 14 and the pipe-section. After the pipe-coupling has been used for a year or two 90 solder or suitable calk material may be placed

in the annular chamber between the collar 14 and the pipe-section in order effectively to prevent any leakage of the coupling. Furthermore, the annular groove 8 in each of the 5 flared ends of the sleeve may be soldered or calked for the same purpose.

In order to reduce friction between the metallic ring 10 and the collar 14, said collar is formed upon the end thereof which abuts 10 against the ring 10 with a plurality of knobs or projections 17. The collar 14 is also formed on its outer surface with a plurality of ribs or projections 18 to provide gripping members for a wrench while placing the coupling 15 in position.

The sleeve 3 adjacent to the end of the pipe-sections 1 and 2 is formed with an annular chamber 19 upon each side of the annular shoulder 5. The annular chambers 19 permit 20 slight movement of the pipe-sections 1 and 2 with respect to each other, whereby an absolutely-rigid coupling is avoided, for which reason, in the event that any bending strain should fall upon the joint, no fracture thereof 25 will result.

The improved coupling of this invention is strong, simple, durable, and inexpensive in construction, as well as thoroughly efficient in use. It is adapted to maintain the ends of 30 a plurality of pipe-sections in coöperative relation with each other without the necessity of forming said pipe-sections with screw-threads or the like. Furthermore, in the event that the coupling shows leakage after 35 several years of use it can be calked or soldered without the necessity of installing an entirely new coupling.

Having thus described the invention, what is claimed is—

40 1. The combination with a plurality of pipe-sections, of a sleeve having screw-threaded ends, each of said ends being formed with an annular groove and a plurality of longitudinal 45 grooves, a packing-ring fitted into each of said ends and surrounding one of said pipe-sec-

tions, a metallic ring abutting against each of said packing-rings, and having a plurality of ears or lugs fitting into the longitudinal grooves of the sleeve, each of said metallic rings having an annular rib thereon adapted 50 to bite into the adjacent packing-ring, and a collar screwed into each end of said sleeve, each of said collars being concentrically removed from the adjacent pipe-section and having a plurality of knobs or projections abut- 55 ting against the adjacent metallic ring.

2. The combination with a plurality of pipe-sections, of a sleeve having its opposite ends formed interiorly with longitudinal grooves, a packing-ring disposed in each end of said 60 sleeve, a metallic ring in each end of said sleeve having ears or lugs fitting into the adjacent longitudinal grooves, and means for retaining each of the metallic rings in position. 65

3. The combination with a plurality of pipe-sections, of a sleeve having flared screw-threaded ends, each of said ends being formed with a plurality of longitudinal grooves and an annular groove, a packing-ring fitted into 70 each of said flared ends, a metallic ring fitted into each of said flared ends and having ears or lugs engaging the longitudinal grooves thereof, each of said metallic rings having an annular rib adapted to bite into the adjacent 75 packing-ring, a collar screwed into each of said flared ends and having a plurality of knobs or projections bearing against the adjacent metallic ring, and an annular shoulder formed on the interior of said sleeve adjacent 80 to the center thereof, said sleeve having an annular chamber upon each side of said annular shoulder. 85

In testimony whereof I affix my signature in presence of two witnesses.

JOHN McDONALD.
